UNITED STATES PATENT OFFICE

WILLIAM M. CAMP, OF NORTH PROVIDENCE, RHODE ISLAND, ASSIGNOR TO J. & P. COATS (RHODE ISLAND) INCORPORATED, A CORPORATION OF RHODE ISLAND

TEXTILE TAPE PACKAGE

Application filed July 22, 1931. Serial No. 552,407.

This invention relates to the packaging of strips of material, more particularly textile fabrics frequently referred to as tape, and has for its object to provide a package of 5 tape having a stiffening core and yet a package from which the tape may be continuously withdrawn.

Another object of this invention is to provide a relatively stiff package of tape or other 10 strip material for easily handling which is folded instead of wound about the core.

Another object of this invention is to provide a package having an envelope, from 15 which the end of the material extends and which material may be drawn completely from the package through an opening in the envelope through which said end extends.

A further object of the invention is the provision of a package having a transparent 20 covering through which the material may be observed and yet protected, with a portion of the material extending through the package and along the outside of the package for more accurate color matching and direct observation as to the texture and quality of the 25 material.

A still further object of the invention is the provision of a package the material of which may not only be observed therethrough but 30 also have a portion exposed for direct observation and color matching, which portion of the material may be grasped to draw additional material from the package to replace the end originally exposed which may have 35 become dirty, soiled or discolored.

With these and other objects in view, the invention consists of certain novel features of construction, as will be more fully described, and particularly pointed out in the 40 appended claims.

In the accompanying drawing:

Fig. 1 is a plan view of the package with portions broken away, showing the different 45 layers of material throughout the package.

Fig. 2 is a section thereof on line 2-2 of Fig. 1.

Fig. 3 is a section on line 3-3 of Fig. 1.

Fig. 4 is a side elevation of the strip of material about the core and showing the manner 50 in which it is folded.

Fig. 5 is a perspective view of the material showing the same as folded about the core with the folded ends in spaced relation.

It has been found desirable in packaging textile fabrics to permit the fabric to be 55 viewed through the package, such as providing the same of transparent material and in addition thereto to provide a portion of the fabric extending outside of the package for direct inspection and color matching, and in 60 addition it is desirable to be able to pull a covered and protected portion of the material from the package should that portion which is originally on the outer surface become 65 soiled or changed in appearance, and I have provided a package which accomplishes these desired results by folding the material about a core in opposite directions so that it may be pulled from the package through an opening therein without disturbing the envelope 70 covering the same; and the following is a detailed description of the preferred means of accomplishing these desired results.

Referring to the drawing, 10 designates 75 generally a sheet of stiff material such as cardboard or the like creased as at 11 to provide a cover 12 to be folded over the core 13 thereof. A strip of tape or other textile material 14 is folded back and forth on itself for a plurality of layers to form a 80 pack, and the folded ends of this pack are then bent or folded about the core 13 in opposite directions to dispose the folds or bights 15 on the back of the core 13 with the ends of the folds spaced as at 16. 85

In order to secure the tape thus arranged upon the core, I fold the cover 12 over the back of the core 13 against the folds or bights 15, as illustrated in Fig. 5, after which a band or wrapper 17 is wound about the textile material and core, which maintains the material in the desired assembled position. The wrapper 17 is provided with an opening 18 through which the end 19 of the textile material extends. 90

There is also provided a "Cellophane" or 95 transparent envelope or covering 20 embracing the textile material, core and wrapper or band, which is also provided with an opening 21 through which the end 19 of the ma- 100

terial also extends and which end is secured to the outer surface of the package or "Cellophane" envelope by a gummed disk 22 which may have any suitable inscription thereon. Also a label 23 may be secured to the end of the strip, as illustrated in Fig. 1 for assistance in removing the sticker 22 when desired.

I have located the openings 18 in the band 10 21 in the "Cellophane" envelope in registry at one side of the package, but these openings may be located in other positions laterally across the package when desired. By extending the end through the registering 15 openings I not only provide means for advantageously matching the color and inspecting the strip but I also provide a construction by which the wrapper 17 is assisted in being held in place centrally of the package 20 or in the desired position in which it is located.

By the construction described I am also able to use a very thin flimsy material such as "Cellophane" or the like to provide an 25 envelope for the package and yet the same is maintained in a stiffened, desired form by the cardboard core about which the material is arranged, the same being permitted to be withdrawn through the covering of the package 30 without removing the covering from its position.

The foregoing description is directed solely towards the construction illustrated, but I desire it to be understood that I reserve the 35 privilege of resorting to all the mechanical changes to which the device is susceptible, the invention being defined and limited only by the terms of the appended claims.

I claim:

40 1. A textile package comprising a thin flat core, a strip of textile material folded back and forth on itself for a plurality of layers to form a pack, the ends of the pack being folded around the ends of the core and extending toward each other along the core, and a flat cover extending along and over the folded ends of the pack to hold the folded ends in position.

45 2. A textile package comprising a thin flat core, a strip of textile material folded back and forth on itself for a plurality of layers to form a pack, the ends of the pack being folded around the ends of the core and extending toward each other along the core, and a flat cover extending along and over the folded ends of the pack and integrally connected to the core to hold the folded ends in position.

50 3. A textile package comprising a thin flat core, a strip of textile material folded back and forth on itself for a plurality of layers to form a pack, the ends of the pack being folded around the ends of the core and extending toward each other along the core, and a flat cover extending along and

over the folded ends of the pack to hold the folded ends in position, and a band about said pack and cover to maintain the cover in holding position.

4. A textile package comprising a thin flat core, a strip of textile material folded back and forth on itself for a plurality of layers to form a pack, the ends of the pack being folded around the ends of the core and extending toward each other along the core, and a flat cover extending along and over the folded ends of the pack to hold the folded ends in position, and an envelope enclosing said pack and cover and holding said cover in position. 70

5. A textile package comprising a thin flat core, a strip of textile material folded back and forth on itself for a plurality of layers to form a pack, the ends of the pack being folded around the ends of the core and extending toward each other along the core, and a flat cover extending along and over the folded ends of the pack to hold the folded ends in position, and an envelope enclosing said pack and cover and holding said cover in position, said envelope having an opening therein through which the strip of material extends whereby said strip may be entirely withdrawn from the envelope through said opening. 85

6. A textile package comprising a thin flat core, a strip of textile material folded back and forth on itself for a plurality of layers to form a pack, the ends of the pack being folded around the ends of the core and extending toward each other along the core, and a flat cover extending along and over the folded ends of the pack to hold the folded ends in position, and a band about said pack and cover to maintain the cover in holding position, said band having an opening therein through which the strip of material extends. 100

7. A textile package comprising a thin flat core, a strip of textile material folded back and forth on itself for a plurality of layers to form a pack, the ends of the pack being folded around the ends of the core and extending toward each other along the core, and a flat cover extending along and over the folded ends of the pack to hold the folded ends in position, and a band about said pack and cover to maintain the cover in holding position, an envelope about said pack core 115 and band said band and envelope having registering opening through which the strip of material extends.

8. A textile package comprising a core, a strip of textile material folded in opposite directions back and forth about said core with the folds adjacent each other on one side of the core, a portion of said core extending laterally beyond the layers of textile material and doubled over said folds, 125

and an envelope of flimsy material covering said package and maintaining the same in desired relation.

9. A textile package comprising a cardboard core, a strip of textile material wound partly about said core in one direction and then doubled upon itself and wound about said core in the opposite direction to meet said doubled portion and then doubled and wound in the first direction, alternating to dispose the material about the core, an envelope about said strip and core with the strip extending through the envelope to be completely pulled therefrom without removing said envelope.

10. A textile package comprising a cardboard core, a strip of textile material wound partly about a portion of said core in one direction and then doubled upon itself and wound about said core in the opposite direction to meet said doubled portion and then doubled and wound in the first direction, alternating to fold the material about the core, the other portion of the core being folded over said doubled portion to maintain the strip in position, an envelope about said strip and core with the strip extending through the envelope to be completely pulled therefrom without removing said envelope.

11. A textile package comprising a cardboard core, a strip of textile material wound partly about a portion of said core in one direction and then doubled upon itself and wound about said core in the opposite direction to meet said doubled portion and then doubled and wound in the first direction, alternating to fold the material about the core, the other portion of the core being folded over said doubled portion to maintain the strip in position, and a band about said folded core and strip of material.

12. A textile package comprising a cardboard core, a strip of textile material wound partly about a portion of said core in one direction and then doubled upon itself and wound about said core in the opposite direction to meet said doubled portion and then doubled and wound in the first direction, alternating to fold the material about the core, the other portion of the core being folded

over said doubled portion to maintain the strip in position, a band of a length less than said core about said folded core and strip of material.

13. A textile package comprising a cardboard core, a strip of textile material wound partly about a portion of said core in one direction and then doubled upon itself and wound about said core in the opposite direction to meet said doubled portion and then doubled and wound in the first direction, alternating to fold the material about the core, the other portion of the core being folded over said doubled portion to maintain the strip in position, a band of a length less than said core about said folded core and strip of material having an opening therein, and the end of said strip extending through said opening.

14. A textile package comprising a cardboard core, a strip of textile material wound partly about a portion of said core in one direction and then doubled upon itself and wound about said core in the opposite direction to meet said doubled portion and then doubled and wound in the first direction, alternating to fold the material about the core, the other portion of the core being folded over said doubled portion to maintain the strip in position, a band of a length less than said core about said folded core and strip of material having an opening therein and the end of said strip extending through said opening, and an envelope about said strip and core with the strip extending through the envelope to be completely pulled therefrom without removing said envelope.

15. A textile package comprising a quantity of strip material disposed in folded form back and forth upon itself for a plurality of layers, a covering for said material a portion of which is transparent and a portion of which is sufficiently stiff to provide a package of the desired shape, said covering having an opening through which an end of said material extends to overlie the outer surface of the package.

In testimony whereof I affix my signature.

WILLIAM M. CAMP.
